UNITED STATES PATENT AND TRADEMARK OFFICE
CERTIFICATE OF CORRECTION

PATENT NO. : Des 452,873 S
DATED : January 8, 2002
INVENTOR(S) : Nakao

Page 1 of 1

It is certified that error appears in the above-identified patent and that said Letters Patent is hereby corrected as shown below:

Title page.

Item [54], the Title should read:

-- [54] **BANK-NOTE CHECKING MACHINE --**

Item [30], the **Foreign Application Priority** information should read:

-- [30] **Foreign Application Priority Data**

Nov. 17, 2000 (JP) ..... 2000-032991 --

Signed and Sealed this

Seventeenth Day of September, 2002

Attest:

Attesting Officer

JAMES E. ROGAN
Director of the United States Patent and Trademark Office
